UNITED STATES PATENT OFFICE.

JANKEL GOLDSTEIN AND BEN ROSENTHAL, OF CHICAGO, ILLINOIS.

DESIGN FOR A WEDDING RING.

Application filed September 28, 1928. Serial No. 28,321. Term of patent 3½ years.

To all whom it may concern:

Be it known that we, JANKEL GOLDSTEIN, a citizen of the Republic of Russia, and BEN ROSENTHAL, a subject of the King of Great Britain, and residents of Chicago, Illinois, have invented a new, original, and ornamental Design for Wedding Rings, of which the following is a specification, reference being had to the accompanying drawing, forming part thereof.

Figure 1 is a perspective view of the wedding ring, showing our new design.

Figure 2 is an enlarged detail view showing a portion of the outer surface of the ring and a portion of the ring being broken away to illustrate a transverse section through the same.

We claim:

The ornamental design for a wedding ring, as shown.

JANKEL GOLDSTEIN.
BEN ROSENTHAL.
